UNITED STATES PATENT OFFICE.

FINIS E. ROACH, OF CHICAGO, ILLINOIS.

CENTRIFUGAL CASTING-MACHINE.

1,362,821.

Specification of Letters Patent. Patented Dec. 21, 1920.

Application filed February 28, 1920. Serial No. 362,018.

To all whom it may concern:

Be it known that I, FINIS E. ROACH, a citizen of the United States, residing at Chicago, in the county of Cook and State of Illinois, have invented certain new and useful Improvements in Centrifugal Casting-Machines, of which the following is a specification, reference being had to the accompanying drawings, and to the reference characters marked thereon, which form a part of this specification.

This invention relates to dental centrifugal casting machines, and consists in the matters herein illustrated and described and more particularly pointed out in the appended claims.

In the drawings:

Figure 1 is a perspective view of a centrifugal casting machine embodying my invention.

Fig. 2 is a top plan view of the same.

Fig. 3 is a vertical longitudinal sectional view, enlarged, of the flask, crucible and associated parts,—the section being taken in the plane indicated by the line 3—3 on Fig. 2.

Fig. 4 is a transverse, vertical sectional view taken on the plane indicated by the dotted line 4—4 of Fig. 2.

Fig. 5 is a detail view showing a pull cord adapted for use in the operation of the machine.

Fig. 6 is a detail view, partly in section, showing a modification in the means for uniting the closed end of the flask to the hooked arm of the machine.

The machine as a whole is indicated by the letter A, and comprises a vertically extending standard or supporting member, and a flask receiving member rotatably secured to the support member. The support member comprises a standard 1, mounted upon a base 2, which may be secured to some rigid part, such as a bench, by bolts placed through the bolt holes 3. The upper end of the support member 1 is T-shaped,—that is to say, it has an elongated tubular head H provided with a longitudinally extending shaft bearing bore or aperture 5, in which the rotatable shaft 6 is journaled, and it has flat or machined end surfaces 4—4. The shaft 6 as shown in Fig. 4 is shorter than the length of the journal bearing 5 and is provided with exteriorly screw threaded ends 7 and 8, each of which, as shown in Fig. 4, projects beyond the ends 4—4 of the head

H. Each of said screw threaded ends 7, 8, is of smaller diameter than the diameter of the shaft 6. 9 is an L-shaped bearing block secured by a key 10 or other suitable means, 60 to a rod 11, which passes through a suitable aperture in the lower end of the long arm of the block 9. This rod 11 is bent upwardly and inwardly toward the block 9 to form a hooked end 12, and carries on its extreme 65 end a small, inwardly extending stud 13.

The upper end of the bearing block 9 is provided with an aperture adapted to receive a sliding rod 14. Through the short end of the bearing block 9 is an interiorly 70 screw threaded aperture adapted to receive the exteriorly screw threaded projecting shaft end 8. The inner end of this projecting shaft end 8 is adapted to engage the sliding rod 14, which preferably will be 75 made flat for a portion of its length to give a better locking bearing to the shaft end 8. It will be noticed that the rods 14 and 11 are parallel and that the axis of the shaft 6 extends in the same plane but at right 80 angles to the axis of the rod 14.

On the outer end of the projecting end 7 of the shaft 6, I secure a pulley wheel 15, the margin 16 of which is preferably knurled so as to afford a convenient hand hold. The 85 pulley 15 is keyed at 7^a to the end 7. The rotation of the pulley wheel 15 to the right moves the screw threaded portion 8 into the bearing block 9 and thus by binding against the side of the rod 14, locks the latter against 90 longitudinal sliding movement with respect to said block 9, as will be readily understood.

It is desirable to hold the rod 14, at times, in a horizontal position. To this end, a lock nut 17 resting upon the screw threaded projection 7 of the shaft 6, intermediate the end 4 of the head H and the pulley wheel 15, is employed. The margin or periphery of the flange 18 of the nut 17 is also knurled at 100 19, to afford a convenient hand hold to manipulate the nut 17. By turning this flanged nut 17 in the same direction as the pulley wheel 15, i. e. in the instance shown to the right, the nut 17 is moved longitudinally along the screw threaded projection 7 until its side face frictionally engages the adjacent end 4 of the head H, thereby clamping the end of the bearing block 9 against the other end 4 of the head H and locking 110 the block 9 in a horizontal or any other desired position with respect to the standard 1.

When the pulley wheel 15 is rotated, *i. e.* in this instance to the right also, such movement tends to move the screw threaded projecting end 7 of the shaft 6 through the lock 5 nut 17 and to loosen the lock nut of its frictional hold upon the end 4 of the head H, thereby automatically unlocking the block 9 and permitting it to be rotated with the shaft 6.

- 10 It will be noticed that there is a slight space 20 between the end of the lock nut 17 and the side face of the pulley wheel 15, when the lock nut 17 is in the position shown in Fig. 4, wherein the bearing block 9 is 15 shown in its horizontal or clamped position. When the block 9 and the pulley wheel 16 and the intermediate shaft are rotated, a space corresponding to that of the space 20 will be opened up between the adjacent end 20 4 of the head H and the lock nut 17. Thus the rotation of the lock nut 17 in one direction, say to the right, will lock the parts together as described, and the rotation of the pulley wheel 15 in the same direction, *i. e.* 25 to the right, will automatically unlock the parts, as before stated.

The rod 14 extends through the bearing block 9, as shown in Fig. 2, on either side thereof, and one end of the rod 14 carries 30 the screw threaded member 21 to which the crucible unit is attached. Said crucible unit embraces an outer end wall 22, a supporting, interiorly screw threaded lug 23 mounted upon the screw threaded member 21 and 35 locked in position by the lock nut 24. Said crucible unit also embraces an interior wall 25, a forward end wall 26 and two side walls 27, 27, and a bottom wall 32. The wall 25 may be brazed or otherwise secured at its 40 margins to the bottom and side walls and the end of the screw threaded member 21 may rest against it, as illustrated in Fig. 3. A crucible member 28 provided with the usual receptacle 29 for molten metal is located within the crucible flask, and at its 45 forward end has an aperture or exit port 30, which registers with an aperture 31 in the wall 26.

The bottom wall 32 of the crucible unit 50 projects beyond the end wall 26 to afford a supporting surface 33 for one end of the bottom wall 34 of the mold flask F to rest upon. This flask member is a rectangularly shaped box, more particularly illustrated in 55 Figs. 1, 2 and 6. At the outer end of the bottom wall 34, an end wall 35 is provided, to which the hooked end 12 of the rod 11 is removably attached. In the form shown in 60 Figs. 1, 2 and 3, this is accomplished by means of an aperture 36 adapted to receive the flanged pin 13 on the hook 12.

The flask also has two longitudinal side walls 38, 38, to which a flanged lid or top cover 37 is hinged at one end, as shown. The 65 mold, designated as a whole by the letter M,

is formed within the flask unit, and the lid 37 closed down before the flask is secured in the position shown in Fig. 3.

When it is desired to place the flask F in the machine, the pin 13 is entered into the 70 aperture 36 in the end of the flask and the rod 14 is moved longitudinally through the block 9 in the direction of the flask until the outside face of the wall 26 presses against the inner edges or margins of the 75 flask unit F, the inner end of the bottom wall 34 resting upon the supporting projecting surface 33 of the bottom wall 32 of the crucible unit. When the parts are thus brought together, as shown in Fig. 3, the 80 pulley wheel 15 is rotated to the right, which causes the screw threaded end 8 of the shaft 6 to engage the sliding rod 14, and thus lock the rod to the block 9 against free longitudinal movement of the rod and at 85 the same time maintain the flask F in operative relation to the crucible unit.

In the pulley wheel 15 is a pin engaging aperture 39 adapted to receive a pin 40 on the one end of a cord 41, a hand hold 42 90 being secured to the other end of said cord 41. When it is desired to operate the machine, the pin 40 is placed in the aperture 39. The cord 41 is wound about the wheel 15 as indicated in Fig. 1 and then the hand 95 hold 42 is grasped and given a strong pull in the direction tending to unwind the cord 41 from the wheel 15. This unwinding causes the wheel 15 to rotate in the desired direction, until the cord 41 is entirely disengaged therefrom, whereupon, as the wheel continues to rotate, the plug 40 is automatically drawn out of the recess 39 and is disengaged therefrom. The wheel 15, however, continues to rotate for some 100 appreciable length of time, perhaps a minute or so. Its rotation causes the rods 11 and 14 and the parts carried thereby, as well as the bearing block 9, to be rotated rapidly about the axis of the shaft 6 as a pivot, 110 thereby generating such centrifugal force as to cause the molten metal lying in the crucible to be projected by centrifugal force and to flow rapidly through the apertures 30 and 31 into the mold M.

As the wheel 15 is being rotated, it is obvious that the screw end 7 of the shaft 6 will move longitudinally through the nut 17, causing the latter to move toward the wheel 15 and fill or partly occupy the space 120 designated at 20. Thus there will be clearance between the end surfaces 4, 4, of the head H and the flange 18 on one end and the block 9 on the other end, whereby the block 9 will freely rotate with the shaft 6 125 during the casting operation.

When the latter is completed and it is desired to remove the flask F, the wheel 15 will be reversed to unscrew the part 8 from the block 9, thus unlocking the rod 14 and 130

permitting of its longitudinal movement through the block 9 in a direction away from the flask. This movement will disengage the pin 13 from the aperture 36 in the 5 flask end, and permit the flask to be bodily removed.

It is manifest from this arrangement that flasks of different length, and to some extent, flasks of different size, may be thus 10 locked and unlocked from the position shown in Fig. 3. In order to give proper counterbalance to the weight of the crucible and flask units when filled, the other end of the slideable rod 14 is screw threaded 15 a considerable distance, as shown at 43, and a balance or counterweight 44 is mounted on said screw threaded part 43 and held in proper position by a lock nut 45.

It will be noticed, by reference to Fig. 2, 20 that the extension 33 of the bottom wall 32 is relatively wide, to provide a good bearing for the flask unit end to rest upon, and also that the side walls 27, 27, are laterally bent at 46 and then forwardly extended at 25 47, so as to accommodate a flask unit relatively wider than that shown in Fig. 2; also that the upper part of the end wall 26 is higher than the height of the flask illustrated (see Fig. 3) and bent forwardly as 30 shown at 48. Thus flasks having heights, widths and lengths different from the relative dimensions of the flask F illustrated, may be used in my machine.

Referring now to Fig. 6, I have illustrated another means of removably securing the flask F and the hook 12. A clamp disk or plate 50, having a raised boss α , (the under side of which forms a recess), is loosely hung on the hook pin 13 which pin 40 passes through a central aperture in said plate and extends into the recess. The plate 50 is secured by flanging the head of the pin 13 as indicated at 13^a. The plate 50 is provided with side lugs Y adapted to embrace the side walls 38 of the flask. It will be understood that the plate 50 will be sufficiently large, and the side lugs Y so spaced apart as to permit of some flexibility, or relative movement with respect to 45 the flask end when said flask is being locked in its position.

It will thus be seen that by my improved construction, the parts are so arranged that the molten metal will readily and very 55 quickly pass through the mold aperture in the flask under the influence of centrifugal force generated by the rotation of the flask and attached crucible; that the flask and crucible may not only be locked together 60 during this rotary movement but may also be held in a horizontal position before rotation, thereby facilitating the handling of materials, the proper positioning of the flask, and the operation of casting. It will also be noticed from the fore-

going that the machine will automatically unlock and permit of the rotation of the rods 11 and 14, the instant that rotation begins.

The machine is neat, cheap to construct, has no complicated parts to get out of order 70 or requiring frequent repair, and is durable and efficient in operation. Except as made the subject of specific claims, I do not desire my invention to be limited to the precise details of construction illustrated and 75 described, as it will be manifest that modifications may be made without departing from the principle and spirit of the invention.

I claim as my invention:

1. A centrifugal casting machine comprising a support, a horizontal shaft rotatably mounted therein, means for rotating the shaft, a bearing block supported on said shaft, a crucible and flask holding frame 85 comprising two members mounted on said bearing blocks, one of said members having slideable movement with relation to said block, and means for locking said sliding member to said block. 90

2. In a centrifugal casting machine having a support, a shaft rotatably mounted therein, means for rotating the shaft, a bearing block supported on said shaft, a flask, an adjustable flask holder comprising a rod 95 secured at one end to said bearing block and having its free end adapted to engage the flask, a second rod slideable longitudinally in said block, means on the slideable rod for engagement with the flask, and means for locking the slideable rod to the block in any desired position whereby the flask will be clamped in operative position. 100

3. In a centrifugal casting machine having a support, a shaft rotatably mounted 105 therein, means for rotating the shaft, a bearing block supported on said shaft, a flask, an adjustable flask holder comprising a rod secured at one end to said bearing block and having its free end adapted to engage the 110 flask, a second rod slideable longitudinally in said block, means on the slideable rod for engagement with the flask, the shaft end being adapted to engage the slideable rod and lock the same to the said block. 115

4. In a centrifugal machine, a vertical support provided with a head at its upper end, a shaft journal bearing extending horizontally through the head, a shaft in said journal bearing of lesser length than said bearing, a reduced part projecting from each end of the shaft beyond the end faces of said head, the outside of each reduced part having screw threads extending in the same direction, means on one of said ends for rotating the shaft, a bearing block rotatably mounted on the other end of said shaft, a frame rod slidably mounted in said bearing block, the longitudinal axes of said rod and shaft being at right angles and so arranged 120 125 130

that the shaft end may frictionally engage the side of the rod to lock the latter to the block.

5. A centrifugal casting machine, comprising a vertical support having a head, a shaft rotatably mounted in said head, means for rotating the shaft, a bearing block movably mounted to the shaft end, a flask, a two part flask holding frame, one part being 10 slidably mounted on the bearing block, means for locking said movable part to said block and means for locking the block to the support head.

6. A centrifugal casting machine, comprising a vertical support having a head, a shaft rotatably mounted in said head, means for rotating the shaft, a bearing block movably mounted to the shaft end, a flask, a two part flask holding frame, one part being 20 slidably mounted on the bearing block, means for locking said movable part to said block and means for locking the block to the support head, said last mentioned means comprising a locking nut mounted on the 25 shaft end opposite the said block.

7. A centrifugal casting machine, comprising a vertical support having a head, a shaft rotatably mounted in said head, means for rotating the shaft, a bearing block movably mounted to the shaft end, a flask, a two part flask holding frame, one part being 30 slidably mounted on the bearing block, means for locking said movable part to said block and means for locking the block 35 to the support head, said shaft having a threaded extension on each end, upon one of which said block is carried and upon the other of which an operating pulley is mounted, the screw threads on each 40 extending in the same direction, and a lock nut mounted on one extension intermediate said pulley and the adjacent head end.

8. In a centrifugal casting machine having a support, a shaft rotatably mounted 45 therein, means for rotating the shaft, a bearing block supported on said shaft and a flask, an adjustable flask holder comprising a rod secured at one end to said bearing block and having its free end adapted to 50 engage the flask, a second rod slidably longitudinally in said block, a counter weight on said second rod, means on the slidable rod for engagement with a flask and means for locking the slidable rod to the block in 55 any desired position whereby the flask will be clamped in operative position.

9. In a centrifugal casting machine having a support, a shaft rotatably mounted therein, means for rotating the shaft, a bearing block supported on said shaft and a flask, an adjustable flask holder comprising 60 a rod secured at one end to said bearing block and having its free end adapted to engage the flask, a second rod slidably longitudinally in said block, a counter weight 65

adjustably mounted on said second rod, means on the slidable rod for engagement with the flask and means for locking the slidable rod to the block in any desired position whereby the flask will be clamped in 70 operative position.

10. In a centrifugal casting machine having a support, a shaft rotatably mounted therein, means for rotating the shaft, a bearing block supported on said shaft and a flask, an adjustable flask holder comprising a rod secured at one end to said bearing block and having its free end adapted to 75 engage the flask, a second rod slidable longitudinally in said block, a counter weight 80 on said second rod on one side of the block and a crucible on the other end of said rod, means on the slidable rod for engagement with the flask and means for locking the slidable rod to the block in any desired position 85 whereby the flask will be clamped in operative position.

11. In a centrifugal casting machine having a support, a shaft rotatably mounted therein, means for rotating the shaft, a bearing block supported on said shaft and a flask, an adjustable flask holder comprising a rod secured at one end to said bearing block and having its free end adapted to 90 engage the flask, a second rod slidable longitudinally in said block, a counter weight 95 on said second rod on one side of the block and a crucible on the other end of said rod, means on the slidable rod for engagement with the flask, means for locking the slid- 100 able rod to the block in any desired position whereby the flask will be clamped in operative position, means on the crucible for supporting one end of the flask and a passageway for molten metal between the 105 crucible and the flask.

12. A centrifugal casting machine, comprising a support, a shaft rotatably mounted therein, means for rotating the shaft, a bearing block supported on said shaft, a two part crucible and flask holding frame, one of which is slidably mounted in said block, means for locking the sliding member of the frame to said block, a flask and means for removably securing the flask to 110 the flask holding frame.

13. In a centrifugal casting machine having a support, a shaft rotatably mounted therein, means for rotating the shaft, a bearing block supported on said shaft and a flask, an adjustable flask holder comprising a rod secured at one end to said bearing block and having a hooked end adapted to 115 engage the flask, a second rod slidably longitudinally in said block and means for locking the slidable rod to the block in any desired position whereby the flask will be clamped in operative position, and means for removably engaging said hook-end with the flask end.

14. In a centrifugal casting machine having a support, a shaft rotatably mounted therein, means for rotating the shaft, a bearing block supported on said shaft and a flask, an adjustable flask holder comprising a rod secured at one end to said bearing block and having a hooked end adapted to engage the flask, a second rod slidable longitudinally in said block and means for locking the slidable rod to the block in any desired position whereby the flask will be clamped in operative position, and means for removably engaging said hook-end with the flask end comprising complementary engaging parts on the flask end and the hook end.
15. In a centrifugal casting machine having a support, a shaft rotatably mounted therein, means for rotating the shaft, a bearing block supported on said shaft and a flask, an adjustable flask holder comprising

ing a rod secured at one end to said bearing block and having a hooked end adapted to engage the flask, a second rod slidable longitudinally in said block and means for locking the slidable rod to the block in any desired position whereby the flask will be clamped in operative position, and means for removably engaging said hook end with the flask end, said means comprising a boss on the flask end and a resiliently mounted member on the hook end adapted for engagement with said boss.

In testimony that I claim the foregoing as my invention I affix my signature in the presence of two witnesses, this 25th day of February, 1920.

FINIS E. ROACH.
